UNITED STATES PATENT OFFICE.

BERNARD R. ANDREWS, OF NEWTON, MASSACHUSETTS.

APPARATUS FOR CONDITIONING AIR OR OTHER GAS.

1,214,114.

Specification of Letters Patent. Patented Jan. 30, 1917.

Application filed August 2, 1915. Serial No. 43,066.

To all whom it may concern:

Be it known that I, BERNARD R. ANDREWS, a citizen of the United States, residing at Newton, county of Middlesex, State of Massachusetts, have invented an Improvement 5 in Apparatus for Conditioning Air or other Gas, of which the following description, in connection with the accompanying drawing, is a specification, like characters on the drawing representing like parts.

10 This invention relates to a device for conditioning air or gas by the use of a conditioning spray, and the objects of the invention are to provide a novel device for this purpose which is simple in construction, extremely effective in operation, in which the conditioning spray is produced automatically by the action of the air or gas current which is to be conditioned or otherwise 15 treated, thus avoiding the use of atomizers or spray devices and the necessary connections and power required to operate them to produce the conditioning spray.

In carrying out my invention I employ 20 a casing containing a body of water and having inlet and outlet openings through which the current of air or gas to be conditioned is caused to pass, and I provide means within the casing which forms with 25 the top surface of the water a more or less constricted passage or throat through which the current of air is forced, the delivery end of said throat or passage being constructed to present a progressively 30 increasing cross-sectional area. I find that with this arrangement the movement of a current of air through the constricted passage or throat and the diverging delivery end thereof will create a conditioning spray 35 which is delivered into the air current.

40 In order to give an understanding of my invention I have illustrated in the drawings a selected embodiment thereof which will now be described, after which the novel features will be pointed out in the appended 45 claim.

Figure 1 is a vertical sectional view of 50 an air-washing device embodying my invention; Fig. 2 is a section on the line 2—2, Fig. 1.

55 1 indicates a casing of suitable proportions which is adapted to contain a body of water and which is provided with an inlet opening 3 and with an outlet opening 4, said openings being situated above the water level so as to permit air to pass through the

casing above the water therein. Any suitable means may be provided for causing the air current to pass through the casing 1. In the device shown in the drawings I have 60 illustrated for this purpose a rotary suction fan 5 which communicates with the outlet or discharge opening 4 and is provided with the tangential discharge 6, said fan being operated from a belt pulley 7. Any 65 other device for causing an air current to pass through the casing 1 may be employed, however, without departing from the invention.

Situated within the casing above the water 70 2 therein and extending from one side to the other is a member 8 which forms with the top surface of the water 2 a comparatively narrow throat 9 communicating with the inlet opening 3. The comparatively- 75 narrow throat 9 leads into the diverging passage 11 through which the air is delivered from the throat 9, said diverging passage being constricted by the space between the top surface of the water and the upwardly-inclined member 12 which extends across from one side to the other of the casing. When the fan 5 is operated a current of air is drawn in through the inlet 3 through the constricted throat 9 and through 80 the diverging discharge end 11 thereof into the casing and the movement of the air current through this passage will create a conditioning spray which is delivered into the air current. It will be noted that one side 85 of the passage including the narrow throat 9 and the diverging space 11 is formed by the top surface of the water, and this is important in producing the desired results. The passage through which the air current 90 is drawn including the constricted throat 9 and diverging discharge end 11 is somewhat analogous both in structure and operation to the well-known Venturi tube. When the air current is being drawn through this passage 95 the static pressure of the air will be less in the constricted portion of the passage than at the inlet port 3 or in the diverging passage 11, and since the upper side of the constricted passage is formed by a non-yieldable plate while the lower side is formed by the surface of the water, the lesser static pressure in the constricted passage will tend to cause the water level to be raised somewhat directly beneath this constricted passage or throat. The current of air passing over this raised body of water 100 105 110

will develop the conditioning spray which is delivered to the current, as above described. With my improved device, therefore, the current of air will be automatically conditioned as it is drawn through the casing 1, and this end is accomplished without the use of any spray devices or other apparatus requiring more or less power to operate them. If this air-conditioning feature ³⁰ is to be used in connection with an air-washing device, then I will provide a plurality of eliminator plates 14 which extend from the top to the bottom of the casing and over which the conditioned air is compelled ¹⁵ to pass, said plates acting in the usual manner to remove the moisture from the air and scrub or cleanse the latter. Some of the eliminator plates herein shown are provided with the curved flange 15 at their delivery ²⁰ end which assists in catching the air and facilitates the washing or scrubbing process.

The device is extremely simple in its construction, but is nevertheless effective in operation. An advantage of the invention is ²⁵ that the only power necessary to condition the air is that required to create the air current, the latter operating automatically to

produce the conditioning spray without the expenditure of additional power for this purpose. ³⁵

While I have illustrated a selected embodiment of my invention, which is sufficient to give an understanding thereof, yet I do not wish to be limited to the constructional features shown. ⁴⁰

I claim:—

In a device of the class described, the combination with a casing containing water, of means forming with the top surface of the water an air passage which presents a narrow throat having a diverging discharge end, and means to cause a current of air to pass through said passage whereby the difference in the static pressure of the air at the constricted portion of said passage and at the diverging end thereof causes a conditioning spray to be developed from the water beneath the constricted portion of the passage, which conditioning spray is delivered to the air current. ⁴⁵

In testimony whereof, I have signed my name to this specification. ⁵⁰

BERNARD R. ANDREWS.
